US0D1073610S

(12) **United States Design Patent** (10) Patent No.: **US D1,073,610 S**
(45) Date of Patent: ** May 6, 2025

(54) **PROTECTIVE COVER**

(71) Applicant: **Dansk Gummi Industri A/S**, Kolding (DK)

(72) Inventor: **Carsten Sommer**, Kolding (DK)

(**) Term: **15 Years**

(21) Appl. No.: **35/517,374**

(22) Filed: **May 10, 2023**

(80) **Hague Agreement Data**

Int. Filing Date: **May 10, 2023**

Int. Reg. No.: **DM/229019**

Int. Reg. Date: **May 10, 2023**

Int. Reg. Pub. Date: **Jun. 2, 2023**

(51) **LOC (15) Cl.** **13-01**

(52) **U.S. Cl.**

USPC **D13/115**

(58) **Field of Classification Search**

USPC D3/202, 203.1, 203.2, 203.3, 272, 273, D3/274, 283, 304, 318, 319; D6/512, D6/513, 540, 552, 553, 567, 574, 702; D7/600.1, 624.1, 387, 388; D9/737, 738, D9/739, 740, 741, 744, 751, 755, 756, D9/759, 500, 501, 502, 503, 414, 418, D9/424, 430, 431, 432, 433, 444, 435, D9/436, 455, 456; D13/118, 133, 154, D13/156, 177, 110, 112, 115, 122, 173, D13/184; D23/411

CPC A47J 47/16; A47B 88/00; A47B 88/40; F01D 5/08
